UNITED STATES PATENT OFFICE

2,657,427

EXTRUSION OF FILAMENT-FORMING MATERIALS

Edward James Upton, Spondon, near Derby, England, assignor to British Celanese Limited, a corporation of Great Britain

Application July 11, 1951, Serial No. 236,130
Claims priority, application Great Britain
July 19, 1950

8 Claims. (Cl. 18—8)

1

This invention relates to the extrusion of filament-forming materials and particularly to a method and apparatus for extruding powdered or granular fusible filament-forming material, and is an improvement in or a modification of the method and apparatus described in U. S. application S. No. 115,035, filed September 10, 1949.

According to the present invention a method of extruding powdered or granular fusible filament-forming material comprises feeding the material into a zone laterally bounded at least part-way round by moving surfaces which lie substantially parallel to their direction of motion, and compacting the material in an early part of said zone so as to form it into a coherent rod and to force it into frictional engagement with said surfaces whereby said rod is advanced with said surfaces, said surfaces being rigidly supported in said early part of said zone, and being resiliently urged inwards of said zone in a later part of said zone whereby said frictional engagement is maintained in said later part. As in the parent U. S. application S. No. 115,035, the advancing rod can be received, as it leaves the surfaces, into a laterally confined space leading to one or more extrusion orifices, the end of the rod being melted in said confined space whereby the molten material is extruded through said orifices by the pressure of the advancing rod.

An apparatus for carrying out the method defined above comprises two endless flexible members arranged to travel past a zone over which they present to each other opposed continuous surfaces each substantially parallel to a common centre line, means for rigidly supporting said members behind said parallel surfaces over a part of said zone, means for resiliently supporting at least one of said members behind said parallel surfaces over a later part of said zone, means for feeding the material into the space between said members and for compacting it into a rod in the first-mentioned part of said zone, and means for driving said members so as to forward the compacted rod.

By the method and means described above the material is compacted into a rod in the first part of a parallel-sided passage, constituting the zone referred to above, whose boundaries are the moving surfaces of the flexible members; the frictional engagement brought about ab initio between the compacted rod and the moving surfaces is maintained over the whole length of the passage, notwithstanding the possibility of slight irregularities in the width of the passage, or of a slight yielding of the substance of the compacted

2

rod. This ensures the distribution of the applied force, necessary for forwarding the rod through a heated extrusion head, over the whole length of the rod contained in the passage. If, as is generally convenient, the passage is partly bounded by stationary walls, these may be arranged to diverge slightly from the centre line of the passage instead of being exactly parallel thereto, or to be relieved slightly following the early part of the passage, so that the frictional engagement of the rod with the stationary surfaces is eased rather than maintained as the rod moves along the passage, and the forwarding of the rod is facilitated. This makes it unnecessary to provide elaborate means for making as many as possible of the bounding surfaces of the passage moving boundaries. Nevertheless, though only two surfaces, opposed to one another, need to be moving surfaces, it is preferred that the passage should be of a rectangular cross-section of which the moving surfaces constitute the longer sides, so as to minimise the area of the stationary surfaces.

The compacting of the granular material in the zone constituted by the passage is conveniently carried out by means of a tamping rod or like member, vibrating longitudinally with its tip disposed between the endless flexible members and tamping the material by repeated impacts in the early part of the zone, over which the parallel surfaces are rigidly supported. Feeding of the material to a tamping rod of this kind can be effected, from one or both sides of the passage, through the stationary walls of the passage by way of an oblique downwardly extending hopper or feed passage communicating through the stationary wall to a point below the uppermost position of the tip of the tamping rod. In order to ensure a steady feed of the material the arrangements described in co-pending U. S. application S. No. 236,129, filed July 11, 1951, may be employed, in which, when the level of the material supplied is low, a consequent change in the mode of motion of the vibrating rod is utilised to effect a movement of the boundaries of the feed passage so as to break down any blocking or "bridging" of material that may have occurred in the passage and so encourage the flow of material down the passage.

By way of example one form of melt spinning apparatus in accordance with the present invention will now be described in greater detail with reference to the accompanying drawings, in which

Figure 1 is a sectional side elevation on the line 1, 1 of Figure 2, and

Figure 2 is a front elevation of the apparatus, partly in section, showing an extrusion head associated with the apparatus and also the vibrator mechanism omitted from Figure 1.

The apparatus comprises a pair of endless triple roller chains 5, 6 each driven by a pair of sprockets 7, 8 each pair of sprockets being mounted on a common shaft 9, 10. The apparatus as shown in Figure 1 is one of a series of units ranged in line and disposed in pairs as may be seen from Figure 2, each pair being provided with a common drive. The common drive is contained in a gear box 11, the shaft 9, 10 being mounted in bearings 12 in opposite walls of the gear box and being common to the two units. The essential parts of the mechanism of the present invention are contained in a casing 13, one of which is fixed on each side of the gear box 11, each of the casings being provided with a cover plate 14 by which the mechanism is enclosed. The shaft 9 is driven from a shaft 15 entering the gear box 11 from the rear, and carrying a worm 16 engaging a worm gear 17 mounted on a shaft 18 in the gear box. The worm gear 17 is secured to a pinion 19 engaging a gear 20 freely mounted on the shaft 9 and secured to a pinion 21. The pinion 21 engages a gear 22 freely mounted on the shaft 18 and secured to a further pinion 23 engaging a gear 24 which is keyed to the shaft 9. The gear 24 also engages a gear of equal size (not shown) keyed to the shaft 10 so that the shafts 9, 10 are driven in synchronism with one another.

The chains 5, 6 are each trained round three idler pulleys 30, 31 and 32 the pulley 30 being a spring-loaded jockey pulley, mounted in a bearing block 33 urged upwards by a spring 34 which is adjustable by means of a screw 35. Each chain 5, 6 carries a series of blocks 36 secured to the middle rollers of the chain. The back of each block 36 is channelled to clear the flat links of the chain 5, 6, but engages and is supported by the rollers of all three lines of rollers in the chain. The operative runs of the two chains 5, 6 are substantially vertical, close to the centre line of Figure 1 and one on each side thereof, the chain moving downwards over this run. The faces of the blocks 36 are covered by two flexible stainless steel bands 39, 40 which leave the blocks between the pulleys 30, 31 to pass round independent jockey pulleys 41 carried in bearing blocks 42, spring loaded by means of adjustable springs 43.

The chain 5 is supported over its operative run by means of a fixed supporting block 44 accurately located and secured to the wall of the gear box 11. At the bottom of the block 44 is a separate piece 45, cut away to accommodate the pulley 32, the block 44 extending down each side of the piece 45 and the pulley 32, the spindle of which passes through the extensions. The block 44 and piece 45 are both channelled and support the chain 5 by the engagement of their edges. The block 44 and piece 45 solidly support the chain 5 over the whole of its operative run from the pulley 31 to the pulley 32.

The operative run of the chain 6 is supported by a series of blocks 48, 49, 50, 51 which are slidably mounted in apertures in a fixed block 52 accurately located and secured to the wall of the gear box 11. The attachment of the block 48 is effected by means of screws 54, passing through a backing plate 55 which engages behind the uppermost aperture in the block 52, and entering the back of the block 48. The block 48 is thus

solidly mounted, and supports the chain 6 rigidly in the same way as the block 44 supports the chain 5. The blocks 49, 50 and 51, however, are not mounted rigidly but resiliently, being slideable in their apertures in the block 52 and being backed separately by plates 56 each of which is urged into engagement with its block 49, 50 or 51 by a pair of strong springs 57. The springs 57 are mounted on studs 58 located in holes 59 in a block 60 accurately located and secured to the wall of the gear box 11. The block 60 carries the bearing block 33 for the jockey pulley 30 engaging the chain 6, and is cut away at the bottom right-hand corner to accommodate the shaft 10. The lowermost aperture in the locating block 52, accommodating the lowermost block 51, extends to the bottom of the block 52, so as to accommodate also the idler pulley 32, the shaft of the pulley passing through the extension of the block 52 on each side thereof. In order to locate the block 51 vertically, horizontal ridges 61 are formed in each of its sides, fitting into horizontal channels in the extensions of the lower end of the block 52. Each of the blocks 48-51 is channelled, like the block 44, for the support of the outer line of rollers of the chain 6.

The space 63 between the operative runs of the chains 5 and 6, which space is bounded on two sides by the surfaces of the bands 39, 40, is bounded on the other two sides by guide plates 64, 65 and upper cheek plates 66, 67 (Figure 2) and lower cheek plates 68, 69 (Figure 2). The lower cheek plates 68, 69 are bolted directly to the wall of the gear box 11, and the cover plate 14 respectively and the guide plates 64, 65 are similarly secured. The upper cheek plates 66, 67 are also bolted to the members 11, 14 respectively but are spaced at a little distance from the members by means of shims 70 so as to be a little closer together than the cheek plates 68, 69, by an amount that can be adjusted by changing the shims 70.

For the feeding of powdered or granular material into the space 63, passages 71, 72 are formed through the lower ends of the guide plates 64, 65, the lower sides of the passages being constituted by the upper surfaces of the cheek plates 66, 67. The passages 71, 72 are led into by ducts 73 supplied from hoppers 74, one hopper being common to each two adjacent units. The passage 71 extends through the guide plate 64, and also through the wall of the gear box 11 and through an inner cover plate 75 disposed inside the gear box 11, to which cover plate a duct 73 is secured. Similarly the passage 72 extends through the guide plate 65, through the cover plate 14, and through an outer cover plate 76 to which another duct 73 is secured. Between the cover plate 75 and the wall of the gear box 11 is disposed a feed gate 77 extending part-way across the passage 71, while between the cover plate 14 and the cover plate 76 is disposed a similar gate extending part-way across the passage 72. The cover plates 75, 76 are channelled on their inner faces to accommodate the gates 77.

In the passage 63 is disposed a vibrating tamping rod 80 actuated by a pneumatic vibrator 81, e. g. of the kind used for the agitation of mould boxes in foundry work, supplied with compressed air by a pipe 82. The tamping rod 80 is guided by the plates 64, 65, and at the bottom of its throw its tip enters between the upper cheek plates 66, 67. The gates 77 are carried on a yoke 84 having lugs 85 (Figure 1) which are guided by slots 86 in the standards 87 carrying the vibrator

81. The yoke 84 is urged downwards to the bottom of the slots 86 by means of a light spring 88 engaging beneath the vibrator 81. A flanged tube 89 is screwed into the bore 90 of the yoke 84 through which the vibrator rod 80 extends, and is locked in adjustable position by means of a lock nut 91. Shoulders 92 are provided on the tamping rod 80 which are adapted, on occasions, to engage the lower edge of the tube 89. These occasions arise in the event of a jamming or "bridging" of the powdered or granular material in the ducts 73, in which case the passage 63 is starved of material and the tamping rod 80, having greater freedom of play downwards, reacts more freely upwards so that the tube 89 is engaged by the shoulders 92. When this takes place, the gates 77 which limit the flow of granular material through the ducts 73 are lifted so as to release the jam. When the supply of powdered or granular material is sufficient, the field of motion of the tamping rod 80 is limited and the shoulders 92 do not engage the tube 89.

The granular material thus fed is compacted into a coherent rod by the tamping rod 80, and the rod is carried downwards by the bands 39, 40 which are caused to maintain their frictional engagement with the compacted rod by reason of the resilience of the support of the backing blocks 48, 50, 51. On reaching the idler pulleys 32 the compacted rod emerges from the passage 63 and enters a guide passage 95 secured beneath the casing 13 and leading to an extrusion head indicated generally at 96 on the left-hand side of Figure 2. The extrusion head 96 is shown in greater detail on the right-hand side of Figure 2, in which the two sides of the head are shown sectioned in two planes at right angles to one another. The head comprises an inlet tube 97 secured to the guide passage 95 by means of a flange 98 engaging beneath a split ring 99 fitting into a groove round the mouth of the inlet tube 97. The flange is drawn upwards by means of nuts 100 on the screws 101 through which the guide passage 95 is secured to the casing 13. The inlet tube 97 extends into a vapour jacket 104, entering through a heat-resisting pressure gland 105, and communicates with a melt tube 106 of thin section, the lower part of which converges (as shown on the right-hand side of the head) and leads into a filter unit contained in a casing 108. The jacket 104 is heavily lagged as at 109 and contains a liquid 110 (such as diphenyl or diphenyl oxide or an azeotropic mixture thereof) which is vaporized in the upper part of the jacket 104 by heat supplied through electrical windings 111. The supply of energy to the windings 111 is controlled so as to maintain a constant pressure of the vapour in the jacket 104, as measured through a pressure take-off passage 112. In this way a constant and controlled temperature is maintained in the jacket 104.

The filter and jet casing 108 contains a stainless steel shell 114 at the top of which two 60 mesh stainless steel gauzes 115 are held beneath a screwed ring 116. Beneath the gauzes 115 is a sand bed 117 of washed sand of a size which will pass a 16 mesh gauze but not a 32 mesh gauze. A clamp ring 118 inside the shell 114 screws down on a series of gauzes 119 comprising two 200 mesh stainless steel gauzes, six 300 mesh Phosphor bronze gauzes and one 200 mesh stainless steel gauze. The bottom of the shell 114 terminates in a slightly tapered boss 120 through which pass a central hole 121, and twelve circumferential holes 122 breaking out into the tapered sides 75

of the boss. Over the boss 120 is fitted a dished jet 123 secured in place by means of a nut 124. The jet and filter assembly is secured as a unit in the casing 108 by means of a nut 125. By removing the filter and jet assembly, and the split ring 99, the entire inlet tube 97 and melt tube 106 can be readily removed for cleaning.

In the operation of the apparatus powdered or granular material is fed to the hoppers 74 and passes through the ducts 73 and the passages 71, 72 into the passage 63 between the bands 39, 40 and between the upper cheek plates 66, 67. The powder is tamped by the tip of the tamping rod 80 into a compacted rod of rectangular section in the part of the passage 63 over which the band 40 is rigidly supported by the block 48 and, by the tamping action, is brought into firm frictional engagement with the bands so that the compacted rod is carried by the bands down the passage 63. Below the block 48 the frictional engagement of the bands 39, 40 with the compacted rod is maintained by the resilience of the springs 57 which urge the blocks 49, 50, 51 inwards. At the same time the frictional engagement of the other two sides of the rod with the upper cheek plates 66, 67 is relieved as the compacted rod reaches the lower cheek plates 68, 69. The friction between the compacted rod and the bands 39, 40 is therefore considerable and the movement of the bands is sufficient to force the compacted rod through the guide passage 95 and the inlet tube 97, into the diminishing cross-section of the melt tube 106. In the melt tube the material of the compacted rod is fused and the fused material is forced, by the pressure of the incoming rod, through the filter unit contained in the shell 114, through the holes 121, 122 at the lower end of the shell, and through the holes in the jet 123, from which the fused material emerges in the form of filaments. The filaments are set by cooling and collected in any convenient way.

As in the parent U. S. application S. No. 115,035, the invention is particularly adapted for the extrusion of organic filament-forming materials that are liable to decompose at temperatures at or only slightly above their melting points, e. g. synthetic linear polyamides, made for example by the condensing of diamines with dicarboxylic acids, or the synthetic polyaminotriazoles (such as polyocta-methylene-aminotriazole) made for example as described in U. S. Patents Nos. 2,512,600 and 2,512,667 or co-polyamide-aminotriazoles, made for example as described in U. S. Patent No. 2,512,627. The invention may also be applied, however, to the spinning of other fusible filament-forming materials, e. g. polyvinyl compounds such as polyvinylidene chloride and copolymers of vinyl chloride with vinyl acetate or acrylonitrile.

Having described my invention, what I desire to secure by Letters Patent is:

1. A method of extruding powdered or granular fusible filament-forming material, said method comprising feeding the material into a zone laterally bounded at least part-way round by moving surfaces which lie substantially parallel to their direction of motion, compacting the material in an early part of said zone so as to form it into a coherent rod and to force it into frictional engagement with said surfaces whereby said rod is advanced with said surfaces, leading the advancing rod as it leaves said surfaces into a laterally confined space having a maximum cross-section substantially equal to that of said

rod and leading to at least one extrusion orifice, melting the end of said rod in said confined space whereby the molten material is extruded through said orifice by the pressure of the advancing rod, rigidly supporting the material inwards of said moving surfaces in said early part of said zone and resiliently urging the compacted rod inwards of said moving surfaces in a later part of said zone whereby said frictional engagement is maintained in said later part and the applied force necessary to produce said pressure is distributed over the whole length of said zone.

2. Method according to claim 1 comprising tamping the material by repeated impacts directed longitudinally of said zone in the early part of the zone so as to compact the material.

3. Apparatus for the extrusion of powdered or granular fusible filament-forming material, said apparatus comprising two endless flexible members arranged to travel past a zone over which they present to each other opposed continuous surfaces each substantially parallel to a common centre line, means for rigidly supporting said members behind said continuous surfaces over a part of said zone, means for resiliently supporting at least one of said members behind said continuous surfaces over a later part of said zone, means for feeding the material into the space between said members and for compacting it into a rod in the part of said zone where said members are rigidly supported, means for driving said members so as to forward the compacted rod, and a heated extrusion head adapted to receive the compacted rod and to melt said rod, said extrusion head being formed with at least one extrusion orifice, through which the molten material is forced by the pressure of the advancing rod.

4. Apparatus according to claim 3 comprising a tamping rod with its tip disposed between the

endless flexible members, and means for vibrating said rod longitudinally so as to tamp the granular material into a rod.

5. Apparatus according to claim 3 comprising stationary walls co-operating with the endless flexible members to constitute a passage.

6. Apparatus according to claim 3 comprising stationary walls co-operating with the endless flexible members to constitute a passage and formed with at least one feed passage therein for the supply of fresh material to the said passage.

7. Apparatus according to claim 6 comprising a tamping rod with its tip disposed between the endless flexible members, means for vibrating said rod longitudinally so as to tamp the granular material into a rod and means adapted to be engaged by said tamping rod upon excess upward motion thereof and to communicate said excess motion to the feed passages so as to encourage the flow of fresh material.

8. Apparatus according to claim 7 comprising a gate extending across the feed passage and adapted to be moved upon excessive motion of the tamping rod.

EDWARD JAMES UPTON.
